METHOD AND APPARATUS FOR CLEANING
OR GRADING SAND OR THE LIKE

Alexander B. Morris, San Antonio, Tex.

Application May 29, 1943, Serial No. 489,092

11 Claims. (Cl. 209—139)

1

This invention relates to a method of and apparatus for cleaning and/or grading for size, sand or other similar substances occurring as aggregations of separate granules.

One example of my invention consists in passing sand downward through a vertical column, over systems of specially arranged baffles, and counter-current to a stream of water flowing upward through the column; the dirt and extremely fine particles of sand passing out of the top of the column with the water, and the coarser particles working their way downward to a suitable sump, from which, as cleaned sand, they may be removed by pump, screw, elevator or other suitable device.

In order to accomplish these purposes, I propose a vertical column into the bottom of which clean water is admitted at a rate of flow such that the upward velocity of the stream through the column itself will be slightly greater than the rate at which the smallest particles desired in the cleaned sand will sink through still water. This inlet for clean water is placed above the sump for collecting the clean sand, or above the port leading to the sump. Above the water intake is the lowest of a series of baffles, each baffle consisting of a series of steps, the treads of which are inclined to the horizontal at an angle greater than the angle of repose of sand in water. These steps extend entirely across the column, horizontally, and through the spaces between them, in the places where there would be "risers" on a flight of steps, the upward-moving column of water passes. Each such step-baffle moves the sand flowing downward over the steps from one side of the column to the other, and the lowest step of each baffle discharges its stream of sand upon the uppermost step of the baffle immediately below it. The step-baffles are so placed in the column that the edges of all the steps on all the baffles are parallel.

Several such step-baffles are placed in the column above the water intake and below the point at which the dirty sand is introduced into the column. The number of such baffles to be used is dictated by the peculiarities of the sand to be washed, and by the degree of thoroughness required in the washing. The sand is introduced into the column in the form of a thin sludge, and upon its entrance it falls upon the top step of the uppermost of the step-baffles described above. As it pours from this step to the step below it, and successively downward and across the column, it falls in a thin curtain across the ascending stream of water issuing from between

2

the baffles, in a direction roughly parallel with the steps. This water is thus imparted a turbulence which extracts from the curtain of sand, all the small particles and retains them in physical suspension, carrying them toward the top of the column. Of course, this turbulence washes out of the sand curtain many particles which are within the size range desired to be kept, and owing to the excess of dirt entering with the sand, the water around the sand intake may take on some colloidal properties and thus entrain many more particles which are desired in the finished product. For this reason, there are placed in the column, immediately above the sand intake, several more step-baffles identical to those already described. Upon these baffles fall all large particles which may have been carried upward with the main water stream due either to turbulence alone, to colloidal characteristics due to excess clays, or to both. Some of these large particles and many which are close to the border line of tolerance for fineness will be carried to the top of the tower.

In order to recover such of these particles as may be within the desired size range, there is placed in the column, above the uppermost of this second set of step baffles, a series of vertical baffles, or straightening vanes, the purpose of which is to break up the turbulent main stream of water approaching the top of the column with its load of dirt and fine particles into a number of small streams, and thus to remove the turbulence and restore conditions of straight-line flow. Above these straightening vanes and occupying the top several feet of the column is an empty chamber the full size of the column and unobstructed by any sort of baffles, the purpose of which is to provide a settling chamber in which may settle out of the now quietly rising water in the column any particles of a size which may be desired in the product and which may have been carried upward to that point. From the top of this settling chamber the water, dirt and silt pass to waste. The rate of input of water is regulated so that the rate of flow upward through the settling chamber will carry away to waste all particles below a certain predetermined size.

Owing to the degree of turbulence imparted to the water in its passage between all these inclined baffles, and to the fact that its direction is roughly parallel to the plane of the steps sufficient turbulence exists to remove and keep in suspension all the clays and fine sand particles. If the raw sand to be washed contains only a relatively small quantity of dirt, the size of the

column can be reduced just below the straightening vanes, and this reduced section carried upward through the settling chamber. In this way, the amount of water required to wash any particular sand can be greatly restricted, since the rate of flow through this part of the column controls the smallest size particle found in the finished product; and a reduction in column cross-section results in a reduced amount of water needed to yield the necessary upward rate of flow.

Some embodiments of the invention are illustrated in the accompanying drawing in which:

Fig. 1 is a vertical sectional view of one form of the apparatus.

Figs. 2, 3 and 4 are horizontal sectional views taken respectively on the lines 2—2, 3—3, 4—4, of Fig. 1.

Fig. 5 is a vertical sectional view of the upper end portion of a modification.

Referring to the drawing, 6 designates a vertical column, supported by a suitable foundation 7 of concrete or the like. The column may be of any preferred shape horizontally and as an example I have shown it of square cross-section. A pipe 8 is employed to introduce fluid, such as water, into the lower end of the column and it may pass through an inclined bottom 9 of the column and terminates immediately above the bottom.

Between the top and bottom of the column a conduit 10 is connected thereto for introducing the sand or the like into the column and this conduit rises, as indicated at 11 and terminates in a hopper 12 which extends upwardly to a higher elevation than the column.

The sand or the like to be treated travels to the hopper by any suitable means, such as an endless conveyor 13, and before dropping into the hopper may be saturated with water discharged through a nozzle 14. The water introduced into the bottom of the column through the pipe 8 passes upwardly and is discharged from the top of the column through a pipe 15 leading to waste, and it will be understood that the water introduced through 8 and 14 will cause the water level at 16 in the hopper to be maintained at an elevation above the top of the column.

Within the column between the sand inlet pipe 10 and the bottom of the column there is a series of superposed baffles 17, 18, 19, 20, and 21 dividing the interior of the column into a series of communicating compartments and arranged zigzag to cause solids to move downwardly in the column from one side thereof to the other. Each baffle consists of a number of strips or treads 22, inclined at about 30° to the horizontal, each baffle being so arranged that it discharges sand from its lowest step up the top step of the next lower baffle. The treads or strips which are supported by opposite walls of the column are spaced apart as indicated at 23 so that the rising water can pass through the openings between the steps. In order to obtain greater turbulence in the lower part of the column, I prefer to have the openings 24 between the steps of one or more of the lower baffles smaller or narrower than the openings between the steps further up.

25, 26 and 27 designate other step-baffles arranged above the sand inlet 10. From the lower edge of the lowest of these baffles, there is a substantially vertical curtain 29 extending downward to within a short distance of the bottom step 30 of the baffle 21 and so placed that it provides a passageway 31 through which the rela-

tively finer material caught on the baffles 25, 26, 27 can be returned to the system without becoming fouled by immediate mixture with the dirty input sand entering through 10.

Above the baffle 25 I arrange vertical parallel straightening vanes 32 which are spaced apart and are connected to opposite walls of the column. Immediately above the vanes 32 there is an unobstructed settling chamber 33 at the top of the column from which the dirty water is discharged through the pipe 15.

It should be observed that the lowest baffle 27 of the upper set is arranged so as to pass the sand in the same direction as the uppermost baffle 21 of the lower set. In other words these two baffles and the steps in them are parallel. I use this arrangement to provide for the quiet passage of fine material behind the curtain 29.

In operation, pit-sand is first rough screened to remove gravel, roots, lump clay, trash, etc., and then screened for the coarsest particles which it is desired to have in the product. The material passing this screen is then slushed into the column through 12, 11, 10, and the water speed through 8 adjusted for removing from the sand thus introduced, all particles below the smallest size desired to be kept. A single passing through one column will yield a mixture almost totally free from particles of less than the minimum desired size. Obviously the heavier particles will gravitate downwardly and eventually lodge in a sump 34 from which they may be removed by any suitable means (not shown).

If grading is desired, a series of similar columns should be used, the pit-sand being first passed through the one of smallest diameter, with the highest water speed through it. The product of this column will be the coarsest grade of sand. The discharge from the first column, instead of going to waste through pipe 15, is introduced into the input pipe 10 of the next column which should be of greater diameter so as to provide a lower water rate through the upper part of the column where actual sorting takes place. A small amount of water should be introduced through 8 at the foot of this column so as to provide a final wash in perfectly clean water. The material collecting in the sump 34 of this second column would be finer than that from the first column. If successively finer and finer grades of product are required, the discharge from the top of the second column can be introduced through the pipe 10 of the third column and so on until all the sand is used up.

If the raw sand to be washed contains only a relatively small quantity of dirt, the size of the column can be reduced just below the straightening vanes as indicated at 35 in Fig. 5, and this reduced section extended upward through the height of the settling chamber as indicated at 36. In this way, the amount of water required to wash any particular sand can be greatly restricted, since the rate of flow through this part of the column controls the smallest size particle found in the finished product, and the reduction in cross-section results in a reduced amount of water needed to yield the necessary upward rate of flow.

For the grading of clean, dry sand, air can be used as the circulating medium and may be introduced through the pipe 8, the only changes required in the apparatus being of degree, such as the angle of slope of the steps of the baffles and the amount of space between them for use with a compressible medium like air. The space

between the steps in each baffle would have to be increased toward the top of the column.

The advantages of this type of cleaning plant over mechanical cleaners now generally used are as follows:

The power required to operate this type of washer is only that needed to drive a pump of sufficient size to deliver the water required.

There are no moving parts to wear or break, and worn baffles can be quickly replaced, thus reducing shut-down time.

The column can be constructed of sewer pipe, wood-stave pipe, or any other kind of pipe, and the baffles can be made of common window glass. Thus, not only can a plant be constructed on any job out of materials readily available; but steel working surfaces are not presented to the moving sand, so that, for glass making, this method of washing and cleaning does not actually put iron cuttings into the sand.

The use of costly heavy moving machinery and the power plant to operate it is avoided.

As the sand progresses down the column it is continually entering cleaner and cleaner water, until it passes through perfectly clean water at the foot of the column. This provides a better degree of washing than any method depending upon agitation of the sand-body in a container from which the water flows over the top; or any method in which the sand-body is kneaded and turned over while water is sprayed upon it.

This method permits the highest degree of cleaning parallel with a minimum of water use. If water is scarce, the height of the column need only be increased, so that the sand makes more transits across the column on its way downward. Since it always ends up in perfectly clean water, it is only necessary to give it enough passes to secure any degree of washing.

Thus this method is highly elastic, from an operating viewpoint. The only element of constancy needed to secure any degree of washing efficiency, is constancy of delivery of clean water. The rate of delivery of dirty sand may vary from zero to 100% column capacity from one minute to the next, without in any way impairing the degree of cleanliness obtained in the product. Overloading the column will result in loss of usable sand in the waste before the appearance of excessively fine particles in the product, and the operation of the plant is undisturbed by anything except too rapid feeding so that the sand enters as heavy slugs. Such slugs will tend to carry dirt to the lower parts of the column so that the final wash water will contain some clay particles. If slugging is avoided, a scrutiny of the particle size in the waste will give an indication of whether or not the column is being over-loaded. It is not necessary to maintain any delicate degree of balance between water and sand input in order for this column to function satisfactorily.

From the foregoing it will be understood that my apparatus depends upon the different rates of settlement in water of particles of varying size. Where broken material of like kind and specific gravity is put into still water the large particles sink rapidly, and the rate of sinking decreases with the particle size, the smallest particles requiring the longest time to settle.

If such loose material is introduced into a tall column of upward rising water at the bottom of which a degree of turbulence is maintained sufficient to keep in suspension all particles smaller than a desired minimum, and at the top of which a rate of vertical non-turbulent flow is main-

tained at a rate somewhat in excess of the rate of settlement of the smallest particles desired to be retained, all smaller particles than the predetermined minimum will be carried toward the top of the column and out with the waste, while all particles of greater size will be collected in the bottom of the column.

In my apparatus this is accomplished by an arrangement of baffles or trays set across the column, sloping at a sufficient angle to cause the loose wet sand to flow from one tray to the next below it; and each such baffle or tray broken up into a plurality of steps, so that each baffle or tray presents the appearance of a small flight of steps having inclined treads with no risers between them. The spaces between the steps on each baffle are equal, but this distance may be varied from baffle to baffle, so that a greater degree of turbulence may be maintained in the bottom of the column by having these spaces smaller in the lower baffles.

The rate of water input is such that, were there no baffles and were the stream of rising water not disturbed, its average speed upward would be sufficient to carry out of the column all particles smaller than a predetermined minimum. However, the inter-position of the baffles increases this speed between them and causes a turbulence which will scour out particles of the desired size even though the average speed of the water is lower than that which would be necessary in an unobstructed column. This turbulence is eliminated in the top of the column by passing the water through a cell of vertical baffles or straightening vanes, and by maintaining in this section of the column, a rate of upward flow sufficient to remove all particles of less than the predetermined minimum. In this top section of the column all particles of greater size than the predetermined minimum are permitted to settle out and return to the system.

While I have disclosed some preferred methods of treating sand or the like and certain practical embodiments for use in practicing the methods, I am aware that changes may be made in the details of the apparatus and in the method steps without departing from the spirit of the invention as expressed in the following claims.

What I claim and desire to secure by Letters Patent is:

1. An apparatus of the character described comprising a substantially vertical column having an upper fluid outlet and a lower solids outlet, first means arranged at one side of the column for introducing loose material consisting of solid particles of various sizes, into the column between said outlets, a curtain arranged in the column diametrically opposite to said first means and forming with the column a substantially vertical passageway, second means for introducing a fluid stream into the column below said first means, a baffle in the column between the first means and the fluid outlet and having a discharge end positioned at the top of said passageway, and a second baffle in the column between the first means and the second means and having a receiving end arranged adjacent to the lower end of said passageway, each of said baffles comprising a plurality of substantially parallel inclined steps spaced from one another and adapted to direct solid particles downwardly from a side of the column toward the opposite side thereof while fluid flows upwardly from said second means through the spaces between the steps and en-

trains light solid particles which discharge with the fluid through said fluid outlet.

2. An apparatus of the character described comprising a substantially vertical column having an upper fluid outlet and a lower solids outlet, first means arranged at one side of the column for introducing loose material consisting of solid particles of various sizes, into the column between said outlets, a curtain arranged in the column diametrically opposite to said first means and forming with the column a substantially vertical passageway, second means for introducing a fluid stream into the column below said first means, a baffle in the column between the first means and the fluid outlet and having a discharge end positioned at the top of said passageway, and a second baffle in the column between the first means and the second means and having a discharge end arranged adjacent to the lower end of said passageway, each of said baffles comprising a plurality of substantially parallel inclined steps spaced from one another and adapted to direct solid particles downwardly from a side of the column toward the opposite side thereof while fluid flows upwardly from said second means through the spaces between the steps and entrains light solid particles which discharge with the fluid through said fluid outlet, both of said baffles being arranged in substantially parallel relation to one another.

3. An apparatus of the character described comprising a substantially vertical column having an upper fluid outlet and a lower solids outlet, first means for introducing loose material consisting of solid particles of various sizes, into the column between said outlets, second means for introducing a fluid stream into the column below said first means, spaced baffles in the column between said first means and each of said outlets, each of said baffles comprising a plurality of substantially parallel inclined steps spaced from one another and adapted to direct solid particles downwardly from one side of the column toward the opposite side thereof while fluid flows upwardly from said second means through the spaces between the steps and entrains light solid particles which discharge with the fluid through said fluid outlet, and means arranged in the column between the first means and the fluid outlet and positioned above the baffles for preventing turbulence of the fluid before the latter reaches the fluid outlet.

4. An apparatus as claimed in claim 3 in which the turbulence preventing means consists of substantially vertical vanes arranged side by side and having their upper edges terminating at a substantially horizontal plane.

5. An apparatus of the character described comprising a substantially vertical column having an upper fluid outlet and a lower solids outlet, first means for introducing loose material consisting of solid particles of various sizes, into the column between said outlets, second means for introducing a fluid stream into the column below said first means, spaced superposed baffles in the column between said first means and each of the outlets, each of said baffles comprising a plurality of substantially parallel inclined steps spaced from one another and adapted to direct solid particles downwardly from one side of the column toward the opposite side thereof while fluid flows upwardly from said second means through the spaces between the steps and entrains light solid particles which discharge with the fluid through said fluid outlet, and substan-

5 tially vertical vanes positioned in the column between said baffles and the top of the column and so arranged as to prevent turbulence of the fluid after it passes through the baffles.

6. An apparatus of the character described comprising a substantially vertical column having an upper fluid outlet and a lower solids outlet, first means for introducing loose material consisting of solid particles of various sizes, into the column between said outlets, second means for introducing a fluid stream into the column below said first means, spaced superposed baffles in the column between said first means and one of said outlets, each of said baffles comprising a plurality of substantially parallel inclined steps spaced from one another and adapted to direct solid particles downwardly from one side of the column toward the opposite side thereof while fluid flows upwardly from said second means through the spaces between the steps and entrains light solid particles which discharge with the fluid through said fluid outlet, the upper end portion of the column being of less cross-sectional area than the portion of the column below, and a series of substantially vertical and substantially parallel vanes positioned in the upper portion of the column above the baffles and so arranged as to prevent turbulence of the fluid after it passes through the baffles.

7. An apparatus of the character described comprising a substantially vertical column having an upper fluid outlet and a lower solids outlet, first means for introducing loose material consisting of solid particles of various sizes, into the column between said outlets, second means for introducing a fluid stream into the column below said first means, a first set of superposed baffles arranged in zigzag formation in the column between said first means and the fluid outlet, a second set of baffles arranged in zigzag formation in the column between the first and second means, each baffle comprising a plurality of substantially parallel inclined steps spaced from one another and adapted to direct solid particles downwardly from one side of the column toward the opposite side thereof while fluid flows upwardly from said second means through the spaces between the steps and entrains light solid particles which discharge with the fluid through said fluid outlet, and means in the column above the first set of baffles for eliminating turbulence in the fluid as it flows toward said fluid outlet.

8. An apparatus of the character described comprising a substantially vertical column provided internally with a series of superposed baffles dividing the interior of the column into a series of communicating compartments, a first outlet for discharging liquid from the uppermost compartment, a second outlet for discharging solids from the lowermost compartment, first means for introducing loose material consisting of solid particles of various sizes, into one of the compartments between the uppermost one and the lowermost one, second means for introducing a liquid stream into the lowermost compartment, each baffle comprising a plurality of substantially parallel inclined steps spaced from one another and adapted to direct solid particles downwardly and transversely of the column while liquid from the second means flows upwardly through the column and through the spaces between the steps, and substantially vertical vanes positioned in the column between said baffles and the top of the column and so arranged as to prevent turbulence of the fluid after it passes through the baffles.

9. An apparatus of the character described, comprising a substantially vertical column having an upper fluid outlet and a lower solids outlet, first means arranged at one side of the column for introducing loose material consisting of solid particles of various sizes, into the column between said outlets, a curtain arranged in the column and forming therewith a substantially vertical passageway, second means for introducing a liquid stream into the column below said first means, a baffle in the column between the first means and the fluid outlet and having a discharge end positioned at the top of said passageway, and a second baffle in the column between the first means and the second means and arranged adjacent to the lower end of said passageway, each of said baffles comprising a plurality of substantially parallel inclined steps spaced from one another and adapted to direct solid particles downwardly and transversely of the column while liquid flows upwardly from said second means through the spaces between the steps and entrains light solid particles which discharge with the liquid through said fluid outlet.

10. In a method of the character described, passing loose material consisting of solid particles of various sizes downwardly through a series of communicating compartments, simultaneously passing a liquid upwardly through said compartments and thereby scouring the particles, maintaining said liquid in the lower compartments at a degree of turbulence sufficient to keep in suspension all particles smaller than a desired minimum, and maintaining non-turbulent flow of the liquid at the uppermost compartment whereby all particles smaller than a predetermined minimum will be discharged with the liquid from the uppermost compartment while all particles of greater size will sink through the liquid and be discharged from the lowermost one of the compartments.

11. In a method of the character described passing loose material consisting of solid particles of various sizes downwardly through a series of alternately arranged spaced baffles and compartments, passing liquid upwardly successively through the compartments and baffles and thereby scouring the particles, maintaining the liquid in the lower compartments at a degree of turbulence sufficient to hold in suspension all particles smaller than a desired minimum, and maintaining non-turbulent flow of the liquid in the uppermost compartment whereby all particles smaller than a predetermined minimum will be carried by the liquid out of the system while all larger particles will sink through the quietly rising liquid and return to the system to be recovered.
